LIGHTING FIXTURE

Application filed August 8, 1929. Serial No. 384,353

The present invention relates to lighting fixtures and is particularly directed toward ceiling lighting fixtures having shielded light sources.

5 The present invention contemplates a fixture more especially designed for installation near the ceiling and wherein a plurality of incandescent lamps carried with their axes horizontal and spaced a short distance above 10 a diffusing glass disk or plate are surrounded by a band or ring which cuts off horizontal light in order to eliminate glare from direct light passing over the edges of the plate.

15 The accompanying drawings show, for purposes of illustrating the present invention, one of the many possible embodiments in which the invention may take form, it being understood that the drawings are illustrative of the invention rather than limiting the same.

20 In the drawings:

Figure 1 is a top plan view of the lighting fixture; and

Figure 2 is a vertical sectional view.

25 The upper part of the fixture may be in any convenient form such for example as the step cast canopy indicated at 10. This canopy is provided with a cross strap 11 and may be secured to the outlet box in any desired manner. It carries a short piece of tubing 12, the 30 lower end of which is threaded as indicated at 14 to support a bushing 15. As here shown this bushing carries three radial tubular arms 16. Each of these arms is connected at its outer end to a downwardly extending connecting strap 17 on which is secured a lamp 35 socket 18. These lamp sockets have horizontal axes and are disposed so as to place the lamp bulbs 19 close to the center of the fixture.

40 The lower end of each of the connecting straps 17 has a drawn tubular threaded boss 20 adapted to receive a screw 21. These screws support a cylindrical band or filament shield 22 spaced from the straps to accommodate fixture wires, and of sufficient width to 45 conceal the light sources and sockets and cut off direct rays of light in a horizontal direction. The nipple fitting 14 is threaded at the bottom to receive another short length of tubing 23. This tubing is threaded into a hickey

24 which supports a diffuser, in the form of a glass plate 25, ornamental disk 26 and knob 27. The lower edge of the band 22 is placed so as to cut off all downwardly emitted light which does not fall on the diffuser.

55 The present fixture is one which is well adapted to give a soft even illumination, as for example in bedrooms, as it conceals the lamps and cuts off all direct rays. The fixture is easily assembled and wired and one can 60 easily remove the glass by taking off the bottom knob to thereby obtain access to the bulbs to clean or change the same.

65 It is obvious that the invention may be embodied in many forms and constructions within the scope of the claims, and I wish it to be understood that the particular form shown is but one of the many forms. Various modifications and changes being possible, I do not otherwise limit myself in any way 70 with respect thereto.

What is claimed is:

1. A lighting fixture comprising a central stem, a plurality of tubular arms extending outwardly from the stem, a lamp socket carried by each arm in a position to dispose an incandescent lamp carried therein with its bulb close to the stem, a band supported from the arms of sufficient width to screen off the 75 sockets and bulbs, and a diffuser underneath the bulbs and band and adapted to receive the downwardly emitted light.

2. A lighting fixture comprising a central stem, a plurality of tubular arms extending outwardly from the stem, a lamp socket carried by each arm in a position to dispose an incandescent lamp carried therein with its bulb close to the stem, a band supported from the arms of sufficient width to screen off the 80 sockets and bulbs, a diffuser underneath the bulbs and band and adapted to receive the downwardly emitted light, and means to detachably support the diffuser.

3. A lighting fixture comprising a central stem, a plurality of tubular arms extending 85 outwardly from the stem, a lamp socket carried by each arm in a position to dispose an incandescent lamp carried therein with its bulb close to the stem, a band supported from the arms of sufficient width to screen off the 90 bulbs and band and adapted to receive the downwardly emitted light, and means to detachably support the diffuser.

sockets and bulbs, and a diffuser underneath the bulbs and band and adapted to receive the downwardly emitted light.

4. A lighting fixture comprising a central stem, a plurality of tubular arms extending outwardly from the stem, straps extending downwardly from the ends of the arm, a lamp socket carried by each strap in a position to dispose an incandescent lamp carried therein with its bulb close to the stem, a band supported from the strap of sufficient width to screen off the sockets and bulbs, and a diffuser underneath the bulbs and band and adapted to receive the downwardly emitted light.

5. A lighting fixture comprising a central stem, a plurality of tubular arms extending outwardly from the stem, straps extending downwardly from the ends of the arm, a lamp socket carried by each strap in a position to dispose an incandescent lamp carried therein with its bulb close to the stem, a band detachably supported from the arms, the band being spaced from the straps to accommodate wires leading to the sockets and of sufficient width to screen off the sockets and bulbs, and a diffuser underneath the bulbs and band and adapted to receive the downwardly emitted light.

Signed at Meriden, in the county of New Haven, and State of Connecticut, this 5th day of August, 1929.
